ENVELOPE

Howard H. Reineman, Brighton, N. Y.

Application January 23, 1933, Serial No. 652,968
Renewed August 12, 1937

12 Claims. (CL 229—81)

The present invention relates to containers or envelopes for holding papers, relatively small articles and the like, and has for one object to provide a container or envelope which can be successively sealed, opened, and resealed whereby to increase its usefulness and to reduce the number of envelopes required for a given service.

A further object of the invention is to provide an envelope having a flap or sealing portion, the inner face of which is adapted to lie upon a portion of the exterior face of one of the walls of the envelope and in which one of said faces is provided with spaced or separate layers of adhesive material for use successively, through cooperation with the other of the faces, to effect sealing, opening, and resealing of the envelope at successive periods.

A further object of the invention is to provide an improved return envelope adapted for holding papers, small articles, and the like, which can be sent by mail or otherwise delivered, and which is capable of being sealed by the sender and subsequently opened by the receiver to effect removal of the contents and resealed with the same or different contents and returned to the sender, or to other persons as desired.

A further object of the invention is to provide an envelope having improved means by which to facilitate easy and relatively quick opening of the same after the closure has been sealed or otherwise secured.

A further object of the invention is to provide an envelope having a flap or other closure, a portion of which is adapted to lie upon a predetermined portion of one of the walls of the envelope, one of the portions having adhesive material thereon for cooperation with the other of said portions to effect sealing of the envelope and said predetermined portion constituting means adapted to be torn off after the envelope is sealed whereby to effect unsealing and release of the closure.

A further object of the invention is to provide an improved envelope having a flap or closure provided with adhesive material for sealing the same upon one of the walls of the envelope and between which and said wall is positioned a part extending laterally from the closure after the latter has been sealed, or otherwise rendered accessible for tearing off by means of the fingers or by the use of other means to effect release of the closure and opening of the envelope.

To these and other ends the invention resides in certain improvements and combinations of parts, all as will be hereinafter more fully de-

scribed, the novel features being pointed out in the claims at the end of the specification.

In the drawing:

Fig. 1 is an elevation of an envelope embodying one form of the invention and showing the envelope closure in open position;

Fig. 2 is a view similar to Fig. 1 but showing the parts in closed and sealed position;

Fig. 3 is a view in elevation showing the relationship of the parts after the closure has been unsealed and opened ready for subsequent sealing, and

Fig. 4 is a view illustrating a modified form of the invention showing the closure in open position, as it appears before sealing.

The same reference numerals throughout the several views indicate the same parts.

The invention is embodied in the present instance, by way of illustration, in an envelope of the type having its opening closed by the folding thereover of a flap or closure which is held in position by suitable securing means such, for example, as adhesive material, which may be applied either to the closure or to that portion of the envelope upon which the closure lies when in closing position.

The present embodiment is particularly adapted for use as a container for photographic film such, for example, as rolls of film or film packs, to be sent to the finisher and adapted to contain also the developed negatives and prints to be returned by him to the sender. Such usage requires closing means capable of being readily secured and released and resecured, and where the container is in the form of an envelope, this is effected by sealing the flap or closure at one or more points with the contents therein. The envelope is then sent to the finisher and the seal is broken by him to release the contents. After the films are developed and printed both are placed in the envelope which is then resealed at one or more points and returned to the sender.

In certain usages it may be desired to seal the envelope at but a single point or in other words to use it without subsequent resealing. In such cases the envelope can be advantageously used, since it is provided with novel and improved means designed to conveniently and quickly effect breaking of the seal and opening of the envelope when desired, as pointed out herein- after.

Referring more particularly to the drawing, there is shown an envelope having opposite side portions 10 and 11, the envelope being preferably formed in a known manner by providing on the

side 11 a longitudinally extending seam comprising the overlapping portions 12 and 13 which are secured one upon another as by means of suitable adhesive material. The side portion 10 is 5 provided in the present instance, with a closure or flap 14 preferably formed integrally therewith and adapted to be folded over the mouth of the envelope and down upon the opposite side portion 11 as shown, for example, in Fig. 2. The 10 free edge 15 of the closure flap 14 is preferably provided with an auxiliary flap 16 forming a coupon slip detachably connected with the closure flap 14 as by means of a scored line at the flap edge 15, this coupon slip being useful 15 for carrying data for identification of the envelope.

In the use of the envelope as a container for photographic film or other articles, the coupon slip may be detached from the envelope and 20 given to the owner of the films at the time they are left for finishing, and he may be required to subsequently produce the slip at the proper time as a means to identify the negatives and prints returned to the sender by the finisher 25 sealed in the same or original envelope.

It has been found that an envelope of the above character may be provided with simple but effective means for securing the closure, which in the present instance comprises a plurality of 30 spaced or separate adhesive surfaces 17 and 18 shown located upon the inner face of the closure 14 but which if preferred may be on the wall 11 of the envelope in position to effect sealing between said wall and the closure when the latter 35 is in the position shown in Fig. 2.

In this position of the closure, following the first sealing operation, the adhesive surfaces 18 are left unmoistened and consequently are unimpaired and are not therefore effective as sealing 40 means between the closure and the wall 11 of the envelope. Sealing is first effected, however, by moistening the adhesive surface 17 and pressing the flap downwardly upon the wall 11, which is preferably provided with a detachable 45 part 19 extending partly beneath the closure and partly at one side thereof and with which the adhesive surface 17 contacts to seal the envelope as shown in Fig. 2.

The tongue-like part 19 preferably comprises 50 a continuation of the overlapping portion 13 of the longitudinally extending seam on the wall 11 of the envelope. The tongue 19 is preferably weakened at its base in order that it may be readily torn off when desired. This may be done 55 in any suitable manner as by providing the perforations 20 which are best shown in Fig. 1 and which extend at one side of the adhesive surface 17 when the closure is in sealing position.

The part 19a of the tongue which is exposed 60 when the closure is in sealing position comprises means which may be grasped by the fingers to permit the tongue to be torn off whereby to effect unsealing and opening of the envelope as shown in Fig. 3, the tearing being facilitated by 65 the perforations 20, or by scoring if preferred. However, instead of employing the fingers to grasp and release the tongue, any suitable instrument may be inserted beneath the same and pressure exerted thereon in a manner to detach 70 the tongue by tearing it along the line of the perforations, thereby releasing the flap or closure and permitting the contents of the envelope to be removed.

When the finisher receiving the envelope un- 75 seals the closure in the manner described he

will then remove the films and complete the developing and printing operations, after which the prints and films are placed within the envelope. Resealing is then effected by moistening the adhesive surfaces 18 and pressing the closure down upon the wall 11 of the envelope. The envelope is then returned to the sender and when received by him is given to the owner when called for, without unsealing if desired, or if preferred it may first be unsealed and the contents inspected to determine the condition of the work and to check the number of articles returned. The unsealing of the envelope after it has been returned to the sender may readily be effected by inserting any suitable instrument beneath the 15 closure and moving it to break the seals, after which the contents can easily be removed from the envelope.

It will be understood that the flap when sealed as shown in Fig. 2 may be opened merely by inserting the finger under the portion 19a of the tongue and moving it toward the end of the envelope to effect tearing of the tongue along the line of the perforations 20.

It will be further understood that the tongue 25 may constitute a separate part inserted between the envelope wall 11 and the flap, in position to register with the layer of adhesive material 17 when the flap is in closing position, in which case a portion of the tongue will extend below 30 the flap as shown in Fig. 2 in position to be grasped by the fingers. Furthermore, the tongue may be formed of fabric, paper, or other suitable material best adapted for the purpose intended.

In the modification shown in Fig. 4 the envelope is constructed in a manner similar to that shown in Figs. 1 and 2, with the exception that the seam portion 13a overlying the portion 12a is cut away at 21 and the detachable part 22 40 comprises a portion of the wall 11a of the envelope and is formed by slotting the latter at 23 and providing the perforations 24 whereby the part 23 may be readily torn off after the envelope has been sealed by moistening the adhesive surface 17a and pressing the closure down upon the body of the envelope.

It will be understood that the flap or closure 12a will have adhesive surfaces thereon corresponding to the surfaces 18 of the flap 14 and 50 that they will be sealed in the manner described in connection with the adhesive surfaces 18 and will function in the same way and for the same purpose.

I claim:

1. A return envelope having a sealing flap the inner face of which is adapted when in sealing position to lie upon the exterior face of one of the walls of the envelope, said wall having a tongue 60 partly exposed and lying partly beneath the flap when the latter is in closing position, said tongue being unattached at one or more of its sides to said wall and rendered detachable by perforations therein adjacent its connection with said wall, one of said faces having spaced adhesive 65 surfaces for use successively through cooperation with the other of said faces to effect sealing, opening and resealing of the flap at successive periods, one of said surfaces being positioned to effect sealing between the flap and the underlying portion of said tongue when the flap is in closing position, the exposed portion of the tongue constituting a part adapted to be grasped by the fingers whereby the tongue may be readily torn off to effect release of the flap.

2. A return envelope having a sealing flap the inner face of which is adapted when the flap is in closing position to lie upon the exterior face of one of the walls of the envelope, said wall having a detachable portion lying beneath the flap, one of said faces having spaced adhesive surfaces and one of said adhesive surfaces being in registry with said detachable portion and serving when moistened to seal the flap upon pressing the latter to closing position upon said exterior face, the removal of said detachable portion serving to open the flap and the latter being adapted for resealing by moistening another of said surfaces and pressing the flap in closing position upon said wall.

3. A return envelope having a sealing flap the inner face of which is adapted when the flap is in closing position to lie upon the exterior face of one of the walls of the envelope, said wall having a portion lying beneath the flap, said portion being weakened on a line extending transversely of the free edge of the flap to render it detachable from said wall, one of said faces having spaced adhesive surfaces for use successively through cooperation with the other of said faces to effect sealing, opening and resealing of the flap at successive periods, one of said surfaces being positioned to effect sealing between the flap and the underlying detachable portion of said wall when the flap is in closing position.

4. A return envelope having one of its side walls provided with overlapping portions secured one upon another and having on its opposite side wall a flap the inner face of which is adapted when the flap is in closing position to lie upon the exterior face of said first mentioned wall, the outer of said overlapping portions having a laterally extending tongue-like extension weakened on a line extending transversely of the free edge of said flap to facilitate its detachment from said wall without separation of said overlapping portions, one of said faces having spaced adhesive surfaces for use successively through cooperation with the other of said faces to effect sealing, opening and resealing of the flap at successive periods, one of said surfaces being positioned to effect sealing between the flap and said tongue-like extension when the flap is in closed position and the detachment of the tongue-like extension serving to open the flap.

5. An envelope having one of its side walls provided with overlapping portions secured one upon another and having on its opposite side wall a flap foldable to engage the first mentioned side wall, the outer of said overlapping portions having a laterally extending tongue-like extension overlying the last mentioned wall and weakened on a line extending transversely of the free edge of said flap and rendered readily detachable by tearing it from said wall without disrupting the same, said tongue-like extension being partly exposed and having its outer face portion lying partly beneath the inner face portion of the flap when the latter is in closed position, one of said face portions having a layer of adhesive material in position to effect sealing between said tongue-like portion and said flap and the flap being opened by tearing off said tongue-like extension.

6. An envelope having a sealing flap for engagement with one of the walls thereof, said wall including a portion the outer face of which is in position to be engaged by the inner face of the flap when the latter is in closing position, said portion being provided with a slot and including a section of a width considerably less than the

length of the flap, said section being weakened at two sides along lines extending from said slot transversely of the free edge of the flap whereby to render said section detachable, one of said faces having a layer of adhesive material in position to effect sealing between the flap and said detachable portion when the flap is in closing position. 5

7. An envelope of the class described having a pocket closed along one edge by the overlapped 10 margins of two different flap portions of the blank of said envelope, said overlapped margins being connected adhesively to each other in a zone of limited area appreciably removed from both ends of said edge, the material of the flap 15 portion which provides the underneath margin having therein means substantially in line with said adhesive zone to form an exposed pull tab appreciably offset from the edge of the uppermost flap portion, whereby a pull on said tab 20 toward said adhesive zone, by tearing of the underneath flap material in a strip embracing said zone, causes said uppermost flap portion to be lifted, for the complete opening of the afore-said closed edge of said envelope pocket. 25

8. An envelope having a pocket closed along one edge by a flap adapted to be lapped over a part of the envelope body, said flap and the overlapped part of the body being adhesively connected to each other in a zone of limited area 30 appreciably removed from both ends of said edge closed by said flap, the portion of said body overlapped by said flap having means substantially in line with said adhesive zone to form an exposed pull tab appreciably offset from the edge of 35 said flap, whereby a pull on said tab toward said adhesive zone will tear the material of the overlapped portion of said body in a strip embracing said zone so that said flap portion may be lifted from said overlapped portion of said body for the 40 complete opening of said closed edge of said envelope.

9. An envelope having a pocket closed along one edge by a flap adapted to be lapped over a part of the envelope body, said flap and the overlapped part of the body being adhesively connected to each other in a zone of limited area, the portion of said body overlapped by said flap having means substantially in line with said adhesive zone to form an exposed pull tab appreciably offset from the edge of said flap, whereby a pull on said tab toward said adhesive zone will tear the material of the overlapped portion of said body in a strip embracing said zone so that said flap portion may be lifted from said overlapped portion of said body for the complete opening of said closed edge of said envelope. 50

10. An envelope having a pocket closed along one edge by a flap adapted to be lapped over a part of the envelope body, said flap and the overlapped part of the body being adhesively connected to each other in only a limited area having a dimension in a direction parallel to said edge of only a minor part of the length of said edge, said area being materially offset from at 65 least one end of said edge, and means weakening said body approximately along at least one edge of said area and so arranged that said area may be lifted with respect to the remainder of said body and torn from the remainder of said body 70 in a direction approximately perpendicular to said edge so that said flap may be turned back to an open position to obtain access to the interior of the envelope through said edge.

11. An envelope having two side walls defining 75

opposite sides of a pocket between them, one of said side walls having a flap hinged thereto along one edge of said pocket, to be folded over the other of said side walls in overlapping relation thereto to close said pocket along said edge, the other of said side walls being formed of a plurality of layers overlapped with each other along a joint line extending at a substantial angle to said edge of said pocket, the outer one of said plurality of layers having a tab portion extending laterally a substantial distance from said joint line in overlapping relation to another of said plurality of layers and in position to be overlapped by said flap when it is folded over to closed position, means adhesively securing said flap substantially only to said tab portion without securing said flap to other portions of said other side wall, to hold said flap in said closed position, and means providing a weakened joint between at least a part of said tab portion and the main body of said outer one of said plurality of layers to assist tearing said tab portion from said main body along a tear line extending in approximately the same direction as said joint line, so that said flap and said tab portion, when adhesively secured to each other, may be lifted with respect to said outer one of said layers to tear said tab portion from the main body of said outer layer

to free said flap so that it may be turned up to open said edge of said pocket.

12. An envelope having two side walls forming between them opposite sides of a pocket open along one edge, a closure flap hinged to one of said side walls along said edge of said pocket and arranged to be folded over the other of said side walls in overlapping relation thereto to close said pocket along said edge, said other of said side walls being formed of two portions overlapped with each other and secured to each other along a zone extending approximately perpendicularly to said open edge of said pocket, the outer one of said two overlapped portions having a tab extending laterally beyond said zone in such position that at least a part of said laterally extending tab beyond said zone will underlie said closure flap when said flap is folded over to its closed position, a substantial part of the area of said tab overlapped by said closure flap being free from direct connection with that part of the inner one of said two overlapped portions which it overlaps, and adhesive for securing said closure flap to at least a portion of said free part of said tab when said closure flap is folded over to its closed position.

HOWARD H. REINEMAN.
